UNITED STATES PATENT OFFICE

CLAIR D. LAKE, OF BINGHAMTON, NEW YORK, ASSIGNOR TO THE TABULATING MACHINE COMPANY, OF ENDICOTT, NEW YORK, A CORPORATION OF NEW JERSEY

CONTROL DEVICE FOR TABULATING MACHINES

Application filed July 31, 1925. Serial No. 47,298.

This invention relates to improvements in tabulating machines and is more particularly directed to improvements in the control devices for machines of this class. Heretofore in tabulating machines automatic control devices were provided which upon an occurrence of a change in control number stopped the operation of the machine and in some instances brought about a printing operation. With previous controlling devices only one control number was utilized, which control number might include several figures. It is one of the principal objects of the present invention to provide a control device which will be applicable for split controlling. The control number instead of being a single number may comprise a plurality of numbers designating different facts. For example, there may be a control number indicative of a customer number, another control number indicative of a salesman number and another one representing a district or state number. In utilizing the split control the machine can be arranged to effect the usual printing operation upon a change in the customer's number and then upon a change in the district or salesman number a different controlling operation can be brought about. In sorting cards preparatory to utilizing them in the machine the user might follow the practice of sorting the cards first by districts, thereafter the district sorted cards would be sorted according to salesman number and finally the salesman cards would be sorted according to customer's number. It will of course be understood that the above sorting and separation of the cards is merely illustrative of one way in which the machine can be used. With this sort of cards the customer's number would be the minor control, the salesman number would be the first major control or group class control and the district number would be the second major or major group class control. As illustrative of the results which would be accomplished with this controlling device the machine could be arranged and so plugged that upon a change in the minor control number, i. e., customer's number, the machine would print a total in the usual way of

amounts represented by that particular customer's number. This operation could of course be performed automatically. The major controls would be separately plugged and when each one of these major controls 55 changed either individually or in combination with another change in the major control number the machine would be automatically brought to a stop and a signal displayed on the particular counter which was 60 accumulating the amounts corresponding to the various control numbers. This signal indicates that one or more changes in major control has taken place and apprises the operator that that particular counter is in 65 condition to have a total printed therefrom and to be reset so that a subsequent tabulating operation can be performed.

In the drawings:

Figure 1 is a circuit diagram. 70

Fig. 2 is a front view of a tabulating machine embodying the present invention.

Fig. 3 is a top view of the machine shown in Fig. 2.

Fig. 4 is a view of the card feeding section of the machine and of the upper and lower brushes. 75

Referring now to the circuit diagram the machine is of the conventional type having upper and lower brushes, B_u and B_l , the upper brushes being connected to the plug sockets 67 and the lower brushes being connected to multiple plug sockets 68. A control unit of conventional type is provided having automatic control magnets 72 suitably connected 80 to plug sockets 670 and 680. The control magnets 72 are arranged to control the closure of the usual automatic control contacts generally designated 73.

In plugging up the machine for control, plug connections would be made between 67 and 670 and between 680 and 68. It will also be understood that the various desired connections would be made between 68 and 69. In place of providing permanent 85 electrical connections between the various contacts 73 as heretofore, these contacts are electrically disconnected from each other and provided with individual plug sockets A, B, C, D, E, F, G, H, L, M, O, P, Q, R, S, T, U, 100

V, W and X. If it is desired to utilize the machine for ordinary controlling work involving, say, eight columns, plug connections would be inserted in connecting sockets B—C, D—E, F—G, H—L, M—O, P—Q and R—S. Plug connection 17 would then be plugged into socket T. A plug connection would also be made between sockets 18 and 20 and between 19 and 21. Control work would now be handled in the usual way. The machine would be automatically brought to stop upon the opening of any of the control contacts 73 inasmuch as the control circuit 74 which is in shunt around contacts C—1 would interrupt the operation of the machine bringing about de-energization of the motor control relay 84. If a less number of columns are to be used for controlling, certain of the plug connections between the upper group of sockets designated A, C, E, G, L, O, Q, S, U and W and lower sockets B, D, F, H, M, P, R, T, V and X would be removed and the plug connection 17 inserted in the proper socket.

It will be assumed that split automatic controlling is desired and that the control contacts are to be split up to control on the customer's number for the first three positions from the right on contacts 73, the salesman number by the next three contacts numbered 4, 5 and 6, and the State or district number by the remaining contacts designated 7, 8, 9 and 0. With this splitting of the control, plug socket 17 would be inserted in socket F as indicated by dotted lines. A plug connection would be made between socket G and plug socket 20. Further plug connection would be made between socket P and socket 18, between Q and 19 and between X and 21. The plugging from the control unit to the upper and lower brushes would be effected in the usual manner. One method of plugging from the lower brushes would be to so plug them that all controlling numbers would be indicated on the first and second counters and so that the sub-totals of amounts by customer number would be indicated in the third counter and the totals of amounts by salesman number would be accumulated in the fourth counter and the grand totals of amounts of State or district number would be accumulated in the fifth counter. As is customary in these machines zero buttons 129 are provided in association with each counter. The zero button in connection with the third counter in the case illustrated would be normally thrown in before running off a tabulated report of this kind, and would always remain in while the zero buttons for the fourth and fifth counters would be out or to the left as looking from the front of the machine. As is customary in these machines when the zero buttons are out there is no printing of a total or clearing of the counter when a reset operation is being effected. In addition to the usual zero button contacts

supplementary button contacts 33 and 32 are provided on the fourth and fifth counters, respectively. Disposed in the circuit from contacts 86 of the motor control relay which formerly extended to binder post 9 through stop key contacts 87 and additional sub-total relay 23 is provided. This sub-total relay is provided with a magnet 22 and its goose-neck and armature are designated at 23. The relay is a back acting relay so arranged that upon energization of magnet 22 contacts 23 will open and also arranged that these contacts will close upon the de-energization of magnet 22. The machine is also provided with two control relays whose magnets are shown at 24 and 25 and whose goose-necks are shown at 26 and 27, respectively. These control relays are so constructed that the energization of magnet 24 causes contacts 28 to open and 29 to close and the energization of 25 causes contacts 30 to open and contacts 31 to close; and vice versa; the de-energization of magnet 24 causes contacts 28 to close and 29 to open and the de-energization of magnet 25 causes contacts 30 to close and contacts 31 to open. As previously explained, additional zero button contacts are provided on the fourth and fifth counters designated, respectively, 32 and 33. A movement of either zero button to the right or in will cause contacts 32 or 33 to close; and vice versa—the movement of the zero button to the left will cause contacts 32 or 33 to open. These contacts 32 and 33 are respectively disposed in a shunt circuit around contacts 29, 31. Connected in circuit to contacts 28 and 30, respectively, are two lamps 35 and 36, the circuit through these lamps being joined at 37 and thence extending through the winding of sub-total relay 22 to a common line 43. A circuit 40 is further provided leading to a common connection extending to cam contacts LP—7 and LP—6, and also to point 39. Circuits 45 and 46 are further provided extending from the opposite sides of contacts LP—7 and LP—6, respectively, to the windings of lamp relays 25 and 24. The circuit leading through winding 24 also extends through cam contacts L—3 to a wire 43 which is connected to the common plug sockets 18 and 19. An additional branch circuit 44 is provided leading from winding 24 to plug socket 20. From winding 25 a circuit leads through cam contacts L—4 to wire 43 and a branch circuit is provided leading to plug socket 21. From plug socket A a circuit 48 extends to binder post 13 which is also connected to binder post 12. A circuit connection 47 is also provided from common plug sockets 19 and 18 to plug socket A.

Operation

When the main switch 81 is closed the two lamps 35 and 36 will light and sub-total relay magnet 22 will be energized thus opening the

motor control circuit at contacts 23. The lamp circuit thus established is traced as follows: from binder post 12 to binder post 13, wire 48, 47, 43 through relay winding 22, lamps 35 and 36, contacts 28 and 30 now closed, through 39 and 40 to the other side of the line. A reset operation must now be made in order to start the tabulator. During this reset operation cam contacts LP-6 and LP-7 close thus supplying current to and energizing windings 24 and 25. As soon as these windings 24 and 25 are energized stick circuits are established keeping the windings energized. One stick circuit may be traced as follows: from left side of line through 40, 39, contacts 29, goose-neck 26, winding 24 and out through 43, 47 and 48 to right side of line. As soon as windings 24 and 25 are energized contacts 28 and 30 will open and the lamps 35 and 36 will become extinguished and the sub-total relay winding 22 will become de-energized. The sub-total relay contacts 23 will then close and the motor control relay contacts 86 will be closed in the usual manner during the resetting operation of the tabulator. It will now be assumed that the tabulator is in operation and the cards are feeding and that the plugging has been made as heretofore indicated. So long as the cards agree in their control perforations the motor control circuit through contacts 23 and 86 is closed at each card cycle which maintains the tabulator in operation. As in previous machines cam contacts C-1 maintain the energization of the usual control relay and the motor control relay. The cam contacts L-3 and L-4 open and close in unison with cam contacts C-1. If the perforations in the cards do not agree in their customer's number the card control circuits through the unit contacts 73 representing positions 1, 2 and 3 of the control unit would be opened at the time cam contacts C-1 open. This opens the motor control circuit contacts 86 in the usual manner, the tabulator then stops at the D position and an automatic reset operation takes place resetting the third counter to zero and subsequently the tabulator restarts tabulating. If the cards do not agree in their control perforations for, say, the salesman number, the card control circuit through the control unit contacts 73 representing positions 4, 5 and 6 of the control unit would be open at the time cam contacts L-3 open. Inasmuch as these particular contacts are in shunt around cam contacts L-3 the opening of cam contacts L-3 would de-energize the counter control lamp relay magnet 24 whereupon contacts 29 would open, contacts 28 would close, the lamp 35 would light, the sub-total relay magnet 22 would be energized, the contacts 23 would open thus opening the motor control circuit and stopping the tabulator at the D position. Although an automatic reset operation would tend to take

place at this time such action would not occur inasmuch as contacts 23 are open and interrupt the automatic reset circuit which extends through cam contacts L-1. As previously explained, lamp 35 is associated with a particular counter on the tabulator, namely, the fourth counter. Illumination of this lamp is a signal for the operator to move the zero button 129 in or to the right. After this is done the hand reset key 243 is now operated. This brings about a printing operation, taking the total standing upon the fourth counter, subsequently clearing the counter and restarting the tabulating operation. The zero button of the fourth counter must now be moved out or to the left.

If the cards do not agree in their control perforations, say, for example, the district number represented by positions 7 to 10 inclusive, the card control circuit through these contacts would open at the time contacts L-4 open. This action would illuminate lamp 36 and stop the tabulator in the manner previously explained. Lamp 36 is associated with counter No. 5 and its illumination indicates that this counter is in condition to have a total taken therefrom and cleared in the manner previously explained for counter No. 4. It will be understood that the reclosure of contacts 32 or 33 by shifting the zero buttons to the in position will effect a re-energization of either windings 24 or 25 and will thus open either contacts 28 or 30. It is necessary that both of these contacts 28 or 30 be opened before the sub-total relay will be de-energized. Winding 22 it will be remembered is de-energized during running conditions of the tabulator and it is only energized to open up the tabulating circuits at 23. The purpose of cam contacts LP-6 to LP-7 is to effect closing of stick circuit, previously mentioned, during the reset cycle to eliminate normal closing of zero button contacts when starting cards through the machine before tabulating operations.

The other circuits shown in the circuit diagram need not be further described as they are more fully set forth in the patent to George F. Daly and Ralph E. Page, No. 1,762,145, issued June 10, 1930.

It will be understood that sub-total relay 22 serves the purpose when energized of automatically stopping the tabulating operations and preventing automatic resetting of the tabulator counter or counters. Resetting is prevented inasmuch as the contacts 23 are disposed in the line leading to binder post 12 from the automatic reset cam contacts L-1. After or when relay 22 is de-energized restarting of the tabulator may take place and automatic resetting can occur.

What I claim is:

1. In a tabulating machine having a control device controllable by separate control

- numbers upon perforated record cards and a plurality of counters into which amounts derived from the perforated records may be accumulated, means controlled by said control device for stopping the tabulating operation, clearing a counter and printing the totals therefrom, and for restarting the tabulator, and means also controlled by said control unit upon the change of a different record card control number for interrupting the automatic restarting of the tabulating until another counter has been selected for clearing and such clearing operation effected. 5 70
- 10 2. In a tabulating machine having a control device controllable by separate control numbers upon the record cards and a plurality of counters into which amounts derived from the perforated records may be accumulated, means controlled by said control device for stopping the tabulating operation, clearing a counter and printing the totals therefrom, and for restarting the tabulator, and means also controlled by said control unit upon the change of a different record card control number for interrupting the automatic resetting of the counters and restarting of tabulating operations until a selection of a counter or counters has been 20 80 made from which amounts are to be printed and the counters cleared. 25
- 15 3. In a tabulating machine having a plurality of counters into each of which items from record cards may be accumulated, and control mechanisms having a plurality of sections each associated with a different counter, means brought into operation upon the change of control number in one section for initiating the stopping of the tabulating 30 90 operation, the clearing of the associated counter and the printing of totals therefrom and for subsequently initiating the restarting of the tabulator, and means brought into operation upon the occurrence of a group 35 100 change in another section for stopping the tabulating operation and designating the section causing the stoppage whereby the associated counter from which a total is to be taken is identified. 40
- 45 4. In a tabulating machine, an automatic control device for modifying the operation of the machine upon the occurrence of changes in group numbers of the record cards, said control device having provision for effecting control from a plurality of groups of record designating perforations, and means for variously signalling the operator of the machine in accordance with various changes which occur in the groups 50 110 of control numbers. 55
- 50 5. In a tabulating machine having an automatic control unit with provision for splitting the same to secure independent controls derived from variously split columns or 60 120 fields of a record card, means under the control of said control unit for bringing about one operation of the machine under a change of one control number and means also under control of said control unit for selectively calling for either of a plurality of other operations of the machine in accordance with the change in either plurality of other control members. 70
6. A tabulating machine having a control unit having a control circuit controlled by control perforations of a record card, means in said unit for splitting the control circuit thereof into separate sections for separate and independent controlling purposes, and a plurality of control devices associated with said separate and split sections of said control circuit for variously controlling the operation of the machine. 75
7. A tabulating machine having a control unit with means therein controlled by the control designating perforations of record cards, means for splitting said unit to effect a plurality of separate controlling operations of the machine which operations are distinctive each to the other and correspond with changes in different control numbers upon the record cards. 85
8. A tabulating machine having a control unit with provisions for controlling the operation of the machine in the usual way upon changes in minor control numbers, in the record cards, said control unit having provisions for splitting the same as desired by the operator to utilize desired sections thereof for a plurality of independent control purposes said plurality of split sections being in addition to the main section for ordinary control and functioning differently upon changes in either of a plurality of major control numbers. 95
9. A tabulating apparatus including a plurality of counters and a control unit means for variously splitting said unit for separate and distinct control purposes which are in addition to the control effected thereby, and means controlled by the split sections of said unit for compelling a selection of one or more counters for clearing and total printing, and means for preventing the normal automatic resetting and restarting of tabulating operations until such selection has been made. 105
10. In a tabulating machine having a plurality of counters, control mechanism comprising a plurality of sections individually associated with different counters, the different sections each including means for controlling machine operation in a distinctive manner to indicate the counter associated with a section which effects a change in machine operation. 110
11. In a tabulating machine having a plurality of counters and means for selecting counters for actuation in certain machine operations, a plurality of control devices individually associated with different counters 125

for separately controlling machine operation and conditioning the machine for further operation on the corresponding counter and means controlled by the separate control devices for indicating the counter associated with a control device which effects a change in machine operation whereby the counter which is to enter into the ensuing machine operation may be identified for selection.
